SAFETY AUTOMATIC LOCK SLIDER

Louis H. Morin, Bronx, N. Y.

Application September 21, 1948, Serial No. 50,359

15 Claims. (Cl. 24—205.14)

1 This invention relates to what is generally known as "automatic lock sliders," employed in conjunction with separable fastener stringers to automatically retain the slider in different positions on the stringers. More particularly, the invention deals with what I term a "safety-type" of automatic lock slider, wherein yieldable means is employed to facilitate movement of a slider along the stringers, as and when the stringers are subjected to an excessive strain, thereby relieving undue stresses or strains on the fastener, as might otherwise prevail, and at the same time, retaining the fundamental, and basic principles or functions of the automatic lock slider.

The novel features of the invention will be best understood from the following description when taken together with the accompanying drawing, in which certain embodiments of the invention are disclosed, and in which the separate parts are designated by suitable reference characters in each of the views, and in which:

Fig. 1 is a sectional view through one form of automatic lock slider, showing my improved construction.

Fig. 2 is a view similar to Fig. 1, showing only a part of the construction and showing a modification.

Fig. 3 is a view similar to Fig. 1, showing the invention applied to another type of automatic lock slider; and

Fig. 4 is a view similar to Figs. 1 and 3, showing my invention applied to another form of automatic lock slider.

In automatic lock sliders of the type and kind under consideration, yieldable means has been provided to normally urge the lock element of the slider into operative or locking position. In many instances, this position of the lock element resulted in a more or less permanent locking of the slider on the stringers, so that when the stringers were subjected to excessive stresses or strains, the slider retained its locked position and some part of the slider would have to yield, thus injuring or destroying the fastener. In other words, the fastener would be rendered inoperative to perform its normal useful function.

It is the purpose of my invention to so modify the structure of automatic lock sliders, as to produce what I term, a safety automatic lock slider, whereby when the fastener is subjected to excessive pull apart strain, the slider will yield to these strains and move along the stringers. In other words, the normal spring actuated lock element of the slider will perform its function to retain the slider against movement on the stringers when subjected to the normal strains, but when the excessive strain prevails, the slider will yield to this strain, thus omitting damage or destruction to the fastener or the separate parts thereof.

In Fig. 1 of the drawing, I have shown my in-

2 vention applied to an automatic lock slider in which the lock element 10 of the slider is in the form of a yoke-shaped arm pivoted to a raised hook-shaped lug 11 on the frog end 12 of a slider 13, by engagement of a pin 14 on the lug. The pin 14 passes through and operates in elongated apertures 15 in the side plates of the element 10, in the manner clearly seen in Fig. 1 of the drawing. The element 10, or the side plates thereof have downwardly directed V-shaped parts, as at 16, for engagement with the scoops 17 of stringers operating in the slider 13.

As the structure of stringers and sliders are generally known in the art, the showing in the drawing is diagrammatic for sake of clarity. The V-shaped projections 16 on the end of the lock element 10, operate in an aperture 18, in the top wall 19 of the slider body.

The hook end 11' of the lug 11 extends into the channel of the lock element 10 and is engaged by a long flat spring 20, secured within the channel of the lock element 10, as indicated at 21. The spring 20 normally urges the lock element 10 in the direction of the arrow 22, to maintain the ends 16 in locked engagement with the scoops 17. At 23 is shown the pivot end of a pull 24. This pivot end is adapted to engage rounded lower surfaces 25 of the element 10 in moving the element 10 into raised inoperative position as the pull is engaged to move the slider 13 along the stringers in both directions.

Secured to the end of the frog 12, of the slider 13 by a rivet or otherwise, as seen at 26, is a flat spring 27, which bears against the end 28 of the lock element and normally supports said end of the element in engagement with the pin 14, as clearly seen in Fig. 1. It will thus be apparent that as the pull 24 is operated to raise the lock element 10, this element is not only raised against the tension of the spring 20, but also acts upon the spring 27. In fact, by modifying the structure of the device, a lock element, such as partly illustrated at 29 in Fig. 2 of the drawing, can be employed. This element differs from the element 10 in comprising a solid bar rather than the channel structure shown in Fig. 1, and being arranged between a pair of lugs 30 having a pivot pin 31, similar to the pin 14. The lock element 29 has an elongated aperture 32, similar to the aperture 15.

In Fig. 2, a spring 27' is employed, which is of sufficient length to engage an offset nose or finger portion 33 on the element 29. With this construction, the one spring 27' may be employed to perform the two functions, namely to urge the element 29 in a direction similar to the arrow 22, Fig. 1, and at the same time, yield to the strained movement of the slider, in which movement, the scoops as at 17, Fig. 1 of the drawing, are moving in a direction of the arrow 34, with respect to the

slider body. In this strained movement, the scoops will force the element 10 outwardly against the action of the spring 27 or the spring 27', as well as against the action of the spring 29, in Fig. 1 of the drawing.

In this strained movement, however, the lock element 10 is free to move longitudinally of the slider, the pivot pin as at 14-31, operating in the elongated aperture 15-32. In the strained movement of the slider on the stringers, it will be understood that the lock element 10 will ratchet over the scoops. In other words, each scoop will perform its function of moving the element into inoperative position against the action of the spring or springs employed.

In Fig. 3 of the drawing, I have shown my invention applied to another type of slider of the kind shown more in detail in my prior application Serial Number 767,815, filed August 9, 1947, now Patent No. 2,535,506, issued December 26, 1950. In Fig. 3, 35 represents the slider body, 36 the transversely arranged lock element having a suitable pivot, as at 37, to swing into and out of the channel 38 of the slider body, through an aperture 39, so as to operatively engage the scoops 40. At 41 is shown a sliding member for actuating the element 36, the member 41 being recessed, as seen at 42, to receive the pivot end 43 of a pull 44, employed to move the member 41 in both directions on the slider body in operating the slider along the stringers.

Arranged within a recessed portion of the slider body is a spring 45 having seats, as at 46 and 47, the spring also seating on downwardly extending lugs 48 and 49 on the member 41. The spring 45 serves to normally retain the member 41 in a position where the downwardly projecting nose 50 of said member engages the element 36 to retain the same in locked position. However, when the member 41 is moved in either direction by the pull, the projection 50 is moved out of engagement with the lock element 36 to facilitate free movement of the slider along the stringers. In the application heretofore referred to, and in which this particular slider is more specifically disclosed, the member 41 is retained in a definite path of movement longitudinally with respect to the slider. Whereas, in the present construction, a flat leaf-spring 51 is secured to the frog end 52 of the slider, as by a riveted pin 53, so that the member 41 can swing upwardly against the action of the spring 51, when the slider 35 is subjected to the excessive strains. In this operation, the element 36 will ratchet over the scoops 40, as with the construction shown in Fig. 1 of the drawing.

It will be apparent that normally, the spring 51 maintains the member 41 in its depressed position, in which position, the member 41 will be free to perform its automatic locking function with respect to action upon the element 36. It is only when the excessive strain prevails, that the member 41 is raised against the action of the spring 51. This raised position of the member 41 is shown in Fig. 3 of the drawing, where the element 36 is passing over the upper or high-point of one of the scoops.

In Fig. 4 of the drawing, I have shown my safety lock principle as applied to the pin lock type of slider. In other words, the pull of the slider includes at its pivoted end portion a lock element. By way of illustration, a slider of the type and kind shown in my prior Patent 2,228,146 granted January 7, 1941, can be referred to.

In Fig. 4 of the drawing, I have shown at 54,

a slider body wherein a pull 55 is employed and the pivot end of the pull as seen at 56 instead of being directly pivoted to the slider body, is pivoted to a supplemental yoke 57, the latter being pivoted to a raised lug 58, on the slider body, as seen at 59. Within the yoke 57 is a ledge or shoulder portion 60 engaged by one end 61 of a coil spring arranged around the pivot 59 within said yoke, the other end 62 of the spring engaging the slider body. This spring will serve to normally support the yoke 57 in the depressed position shown in full lines in Fig. 4 of the drawing. Another coil spring 63 is arranged around the pivot 56 of the pull within the yoke 57, one end 64 of the spring engaging the yoke and the other end 65 being fixedly secured to the pull, the spring being tensioned to normally support the pull in the depressed or full line position shown in Fig. 4. Integral with the pivot end of the pull is a wedge-type lock pin or element 66, which operates in an aperture 67 in one wall 68 of the slider body, so as to operatively engage the scoops 69.

With the full line position of the parts as shown in Fig. 4, the element 66 is in its normal locking position, in which the slider 54 is retained against movement along the stringers, or in other words, relatively to the scoops 69. However, if the pull is subjected to excessive strain, the scoops moving in the direction of the arrow 70 of Fig. 4, with respect to the slider body, will engage the element 66, and force it into raised position, as indicated in dot and dash lines, which movement is performed directly against the action of the spring arranged upon the pivot 59. As with the other structures, the lock element 66 will ratchet over the scoop 69 in this operation. However, in normal operation of the slider through the medium of the pull 55, the lock element 66 will be moved out of engagement with the scoops 69 in the normal swinging of the pull on the pivot 56. In some instances, this operation of the pull may also swing the yoke 57 on its pivot to some extent. This swinging movement, however, is checked by the pivoted surface 71, at the pivot end of the yoke, striking the upper surface 72 of the slider.

With all forms of construction shown, the automatic lock principle of the slider is not interfered with or disturbed in any way. However, means is provided in each instance, to facilitate ratcheting movement of the slider along the stringers, in the event that the stringers are subjected to an excessive pull apart stress or strain. These stresses or strains are often experienced in connection with uses of the fastener on garments, and particularly the application of fasteners to trousers. In all instances, the spring tension of the strain-relief safety factor of the device, will be controlled and regulated to suit installations or uses of the fastener. In this connection it will be understood that in some instances, the stresses or strains are materially greater than in others. It will also be apparent that in the several uses of the invention, as herein disclosed, the normal functioning and operation of the pull is not interfered with or modified, except to the extent where operation of the pull can react upon the additional tensional means employed. This is particularly true in the construction shown in Figs. 1, 2 and 4 of the drawing.

It will appear from a consideration of the several devices, that the lock element or the member controlling the lock element, in all instances, is capable of two distinct movements.

In Figs. 1 to 3 inclusive, there is present the combination slide and swinging movement, whereas in Fig. 4, two distinct swinging movements are provided. One, the swinging movement of the pull on its pivot, and the other, the swinging movement of the yoke to which the pull is pivoted. It is the combination of these two movements which produces the conventional automatic lock slider, plus the safety-lock factor, which allows the lock element to yield when subjected to excessive strains.

Having fully described my invention, what I claim as new and desire to secure by Letters Patent is:

1. An automatic lock slider for separable fastener stringers comprising a channeled slider body, a lock element on said body movable into the channel thereof to engage scoops of a separable fastener stringer to normally retain the slider against movement on the stringers, yieldable means for retaining the lock element in scoop-engaging position, a member movably supported on said body and supporting said lock element for enabling the lock element to be displaced from scoop-engaging position when the stringers are subjected to excessive pull-apart strains said lock element being pivotally connected to said member, and tensional means independent of said yieldable means for restraining said member against movement on the slider body when the slider is in a normal locked position on the stringers.

2. In a lock slider for separable fastener stringers comprising a channeled body movable along said stringers to couple and uncouple the same, a lock element movably supported on said slider and including a lock pin movable into and out of the slider channel for engaging scoops of said stringers, a member yieldably supported on said slider and biased so as to act against said lock element, said member being yieldable to enable the lock pin to ratchet over the scoops when the stringers are subjected to excessive strains, and spring means for retaining the lock element and lock pin in scoop-engaging position to arrest the slider against movement under normal strains.

3. In a lock slider for separable fastener stringers comprising a channeled body movable along the scoops of a pair of stringers, a pull-supporting member pivoted to the slider and movable longitudinally thereof, a lock pin at one end of said member, said member serving to move said pin into and out of the channel of said body to engage the scoops of the stringers, a spring for urging the lock pin into engagement with the scoops, and a tension member on said slider acting on said pull-supporting member and serving normally to maintain the lock pin in engagement with said scoops, said tension member being sufficiently yieldable to enable the pull-supporting member to be moved thereagainst and the lock pin moved out of said channel by the action of said scoops when the stringers are subjected to excessive pull-apart strains.

4. In a lock slider for separable fastener stringers comprising a channeled body movable along the scoops of a pair of stringers, a pull-supporting member on the slider and movable longitudinally thereof, a lock pin at one end of said member and movable into and out of the channel of said body by the action of said member, a spring acting on said member for urging the lock pin into engagement with the scoops, and a tension member on said slider acting on

said pull-supporting member, said tension member being sufficiently yieldable to enable the pull-supporting member to be moved thereagainst and the lock pin moved out of said channel by the action of said scoops when the stringers are subjected to excessive pull-apart strains.

5. In a lock slider for separable fastener stringers comprising a channeled body movable along the scoops of a pair of stringers, a pull-supporting member pivoted to the slider and movable relatively thereto, a lock pin adjacent one end of said member movable into and out of the channel of said body to engage the scoops of said stringers, a spring for urging the lock pin into engagement with the scoops, and yieldable means on said slider acting on said pull-supporting member, said means being sufficiently yieldable to enable the pull-supporting member to be moved thereagainst and the lock pin moved out of said channel by the action of said scoops when the stringers are subjected to excessive pull-apart strains.

6. In a lock slider for separable fastener stringers comprising a channeled body movable along the scoops of a pair of stringers, a pull-supporting member on the slider and movable relatively thereto, a lock pin adjacent one end of said member movable into and out of the channel of said body to engage the scoops of said stringers, a spring for urging the lock pin into engagement with the scoops, and yieldable means on said slider acting on said pull-supporting member, said means being sufficiently yieldable to enable the pull-supporting member to be moved thereagainst and the lock pin moved out of said channel by the action of said scoops when the stringers are subjected to excessive pull-apart strains.

7. In a lock slider for separable fastener stringers comprising a channeled body movable along said stringers to couple and uncouple the same, a lock element movably supported on said slider for locking the same to said stringers, spring means for retaining the lock element in locking position under normal strains, a pull handle for moving said lock element to unlocking position against the action of said spring means, and a member yieldably supported on said slider and biased against said lock element, said member being yieldable to enable the lock element to ratchet over said stringers when the stringers are subjected to abnormal strains.

8. In a slider for separable fastener stringers having upper and lower plates connected by a web, a lug projecting from the upper plate adjacent the web end of the slider, an opening in said plate adjacent the other end thereof, a portion of the opening on the side nearer to said lug being defined by an inclined wall, a locking arm pivotally mounted on the lug and partially enclosing the same, a locking projection on said arm spaced from the lug and movable through said opening to engage said stringers, said locking projection having an inclined surface engageable with and slidable over said inclined wall of said opening, a slot in that portion of the locking arm enclosing said lug, a pin in the lug extending into and engageable by said slot, whereby the locking arm is adapted to be moved pivotally and longitudinally with respect to said slider, a spring on said slider for normally urging said locking projection into locking engagement with the stringers, a pull for engaging the locking arm and adapted to move the locking projection out of locking position, and

yieldable means on the slider for yieldably supporting the locking arm and for enabling said arm to be moved out of locking position by the stringers when the fastener is subjected to abnormal strains tending to open the fastener.

9. In a slider for separable fastener stringers having upper and lower plates connected by a web, a lug projecting from the upper plate adjacent one end of the slider, an opening in said plate adjacent the other end thereof, an inclined wall defining said opening, a locking arm pivotally mounted on the lug, a locking projection on said arm movable through said opening to engage said stringers, said locking projection having an inclined surface engageable with and slidable over said inclined wall of said opening, interengaging means on said locking arm and lug comprising a pin and slot for enabling the locking arm to be moved longitudinally of said slider, a spring on said slider for normally urging said locking projection into locking engagement with the stringers, a pull for engaging the locking arm and adapted to move the locking projection out of locking position, and yieldable means on the slider for yieldably supporting the locking arm and for enabling said arm to be moved out of locking position by the stringers when the fastener is subjected to abnormal strains tending to open the fastener.

10. In a slider for separable fastener stringers having upper and lower plates connected by a web, a lug projecting from the upper plate, an opening in said plate spaced from said lug, an inclined wall defining said opening, a locking arm mounted on the lug for pivotal and longitudinal movement relatively to the slider, one end of said arm being movable through said opening to engage said stringers and having an inclined surface engageable with and slidable over said inclined wall of said opening, a spring on said slider for normally urging said locking arm into locking engagement with the stringers, a pull for engaging the locking arm and adapted to move the same out of locking position, and yieldable means on the slider for yieldably supporting the locking arm and for enabling said arm to be moved out of locking position by the stringers when the fastener is subjected to abnormal strains tending to open the fastener.

11. In a lock slider for separable fastener stringers, a lock element pivotally mounted at one end portion of the slider to swing vertically in a transverse plane with respect to the slider, a movable member mounted to move longitudinally of the slider body and at right angles to the swinging movement of said lock element, said member having parts for engaging the lock element to move the latter into and out of locking position, spring means normally supporting said member in a position wherein the lock element is held in a locked position, a pull for moving said member in either direction from said normal position against the action of said spring to a position wherein the lock element is unlocked, and a yieldable member on said slider for yieldably supporting said movable member and for enabling the lock element and said movable member to be moved out of locking position by the stringers when the fastener is subjected to abnormal strains tending to open the fastener.

12. In a channeled fastener slider of the kind including a lock piece movable relatively to the slider into and out of channel-blocking position, the combination of a lock piece actuator mounted on the slider for lengthwise sliding movement

5

respectively thereto, stop means for limiting the lengthwise travel of the actuator, spring means engaged with the slider and engaging the actuator and biassing the latter to a mid-position with respect to its travel limits, the actuator having a portion engageable with the lock piece to move the latter into channel-blocking position to lock the slider against normal strains, a pull for moving the actuator, and yieldable means on the slider for yieldably supporting the actuator and for enabling the lock piece and the actuator to be moved out of channel-blocking position by the stringers when the slider is subjected to abnormal strains tending to open the fastener.

15

13. In a slider for separable fastener stringers comprising a double-walled web-connected body, a lug on the upper wall and an opening in said wall spaced from the lug, a yoke member pivoted to the lug, a pull on said slider having a locking pin, said pull being operatively positioned to move the locking pin through said opening to lock and unlock the slider to said stringers, said pull being pivotally supported by the yoke member in said operative position, spring means for urging the pull and pin into slider locking position to lock the slider against normal strains, tension means on the slider for holding the yoke member in said pull-supporting position and for enabling the yoke member to be moved out of said position and the pull and pin to be moved out of locking position when the slider is subjected to abnormal strains tending to open the fastener.

20

14. In a slider for separable fastener stringers, a yoke member pivoted to one wall thereof, a pull on the slider having a locking pin, said pull being operatively positioned to move the locking pin into and out of locking position, said pull being supported by the yoke member in said operative position, spring means for urging the pull and pin into slider locking position to lock the slider against normal strains, yieldable means on the slider for yieldably holding the yoke member in said pull-supporting position and for enabling the yoke member to be moved out of said position and the pull and pin to be moved out of locking position when the slider is subjected to abnormal strains tending to open the fastener.

30

15. In a slider for separable fastener stringers, a lug on one wall of the same and an opening in said wall spaced from the lug, a member pivoted to the lug, a pull pivoted to the member, a locking pin on the pull, said pull being operatively positioned with respect to said member so as to move the locking pin through said opening to lock and unlock the slider to said stringers, spring means for urging the pull and pin into slider locking position to lock the slider against normal strains, yieldable means on the slider acting on said member for yieldably holding the member and thus the pull in said operative position and for enabling the member and pull to be moved out of said position and the pin to be moved out of locking position when the slider is subjected to abnormal strains tending to open the fastener.

40

16. In a slider for separable fastener stringers, a lug on one wall of the same and an opening in said wall spaced from the lug, a member pivoted to the lug, a pull pivoted to the member, a locking pin on the pull, said pull being operatively positioned with respect to said member so as to move the locking pin through said opening to lock and unlock the slider to said stringers, spring means for urging the pull and pin into slider locking position to lock the slider against normal strains, yieldable means on the slider acting on said member for yieldably holding the member and thus the pull in said operative position and for enabling the member and pull to be moved out of said position and the pin to be moved out of locking position when the slider is subjected to abnormal strains tending to open the fastener.
